United States Patent Office.

JOSEPH W. MOORE, OF CAMBRIDGEPORT, MASSACHUSETTS.

Letters Patent No. 72,218, dated December 17, 1867.

IMPROVED SLOTTING-MACHINE.

The Schedule referred to in these Letters Patent and making part of the same.

TO ALL WHOM IT MAY CONCERN:

Be it known that I, JOSEPH W. MOORE, of Cambridgeport, in the county of Middlesex, in the State of Massachusetts, have invented a new and improved Mode of Cutting Key-Seats in Couplings, Gears, &c.; and I do hereby declare that the following is a full and exact description thereof, reference being had to the accompanying drawings, and to the letters of reference marked thereon.

The nature of my invention consists in having an iron plate with an upright standard so arranged as to admit of an iron shaft passing through it into an oscillating box attached to a frame, into two upright standards, the whole to be firmly secured to the bed-plate of an iron-planer.

To enable others skilled in the art to make and use my invention, I will proceed to describe its construction and operation.

I construct a plate with an upright standard at the end, as represented by A and B, Figure No. 1, with a small rib on the bottom, as represented by G, Figs. Nos. 1 and 2. On the top of plate A is a raised rib, planed in bevelled form, as represented by F in Nos. 1 and 2. I then construct a plate with two standards, as represented by C in No. 1, and C C, No. 2, which are grooved from top to bottom, as represented by h h in Figure No. 3. I then make a small iron frame, as represented by O O, for the purpose of holding the oscillating box D, as represented in No. 2. A screw is attached to the iron frame passing up through cap E, on which are two lock-nuts k k, the object of the screw being to raise this box to any position required. When in position, the lock-nuts are firmly screwed down to cap E, which secures it to that position as a gauge until the work is finished. I now construct a jointed shaft, m m m n, as represented in No. 1; the joint n being square. In the shaft m m n is the cutter L. Letter I represents a coupling in position for grooving, firmly bolted to the face-plate B.

The operation of my invention is as follows: The machine being firmly bolted to the planer-bed, the square part of the jointed shaft n is firmly attached to the tool-stock of the planer. The coupling being in position as required, the planer is put in motion, which carries the machine forward. The tool-stock being stationary, the shaft is not allowed to move with the machine, and being guided by the oscillating box D, it will readily be seen any depth of groove can be cut by the raising and falling of the tool-stock of the planer.

What I claim as my invention, and desire to secure by Letters Patent, is—

The combination of mechanism as described, for the purpose set forth, and for the object specified.

JOS. W. MOORE.
